Attorney

UNITED STATES PATENT OFFICE.

EARNEST A. WARNER, OF BEACH, NORTH DAKOTA.

SPARK-PLUG.

1,837,169.

Specification of Letters Patent. Patented Apr. 13, 1920.

Application filed May 8, 1917, Serial No. 167,208. Renewed January 12, 1920. Serial No. 350,940.

To all whom it may concern:

Be it known that I, EARNEST A. WARNER, a citizen of the United States, residing at Beach, in the county of Golden Valley and State of North Dakota, have invented certain new and useful Improvements in Spark-Plugs; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

The invention has reference to spark plugs for internal combustion engines, and particularly what are known as testing spark plugs.

20 The primary object of the invention is to provide a spark plug of this character which will enable the operator to detect the inoperativeness of the plug, without the necessity of removing the same.

25 A further object of the invention is to provide a combined spark plug and intensifier.

30 A still further object of the invention is to provide means for adjusting the intensifier points and consequently varying the distance of spark gap.

Referring now to the drawing, Figure 1 illustrates a longitudinal sectional view through the spark plug. Fig. 2 is a detailed view of the inner shell and Fig. 3 is a perspective view.

In the drawing, the numeral "5" indicates an outer shell carrying the stationary electrode 7 and having a lower threaded portion 6 to permit the same to be positioned within a threaded opening of an engine cylinder.

An inner metallic shell 8 is spaced from the outer shell 5 by means of the spacing sleeve 9 threaded within shell 5. This shell 8 is provided with openings 10, disposed diametrically opposite each other, and register with an opening 11, formed transversely through the core 12, positioned within the shell 8, and insulated therefrom by means of the tubular transparent insulating member 13, surrounding that portion of the core 12 which would otherwise come into contact

with the metallic shell 8, and at the same time covering the opening 10 of the shell 8. 55

Disposed centrally of the core 12 is a broken electrode comprising an upper threaded or adjustable section 14, and a lower section 15, the lower end of the upper section 14 and the upper end of the 60 lower section lying within the opening 11 of the central core 12, and in a position to be viewed through the openings 10 of the shell 8. The lower end of the lower section 15 of the electrode lies in close proximity 65 to electrode 7 to permit the usual sparking to take place therebetween.

A threaded washer 16 is positioned on the threaded portion 14 of the broken electrode and insulated from shell 8 by means 70 of insulating washers 17, and it will be seen that by screwing the threaded washer 16 into engagement with the shell 8, vertical movement of the section 14 is prevented.

In order that the upper portion 14 of the 75 electrode may be adjusted, the upper end thereof is provided with a notch 19 to receive a screw-driver or other similar instrument. The ordinary binding nut 20 is also positioned on the upper threaded section 14 80 to permit a cord terminal to be attached thereto.

From the foregoing, it will be seen that when electric current passes through the electrodes of the spark plug, a spark is necessarily formed between the sections 14 and 15, which spark not only intensifies the current, but permits the operator to observe the same through the opening 10 of the shell 8 and thereby, detect whether or not the 90 same is operating.

What I claim:

A spark plug having a terminal at one end, and having a shoulder in the bore thereof, a cylindrical core with a shoulder 95 adapted to rest upon the shoulder in said plug, one end of the core having a reduced portion terminating in a curved shoulder, said core having a longitudinal aperture extending its entire length and intersecting 100 a transverse opening therein, a shell fitted over the core and resting upon a shoulder within said plug and its outer end inwardly curved and apertured, the portion above said aperture resting upon the shoulder at 105

the contracted end of the core, terminals fitted within the core and spaced apart at the opening therein, a threaded screw upon one of the terminals adapted to hold the same in an adjusted position, and an interiorly and exteriorly threaded cylindrical nut holding the shell within said plug.

In testimony whereof I hereunto affix my signature in presence of two witnesses.

EARNEST A. WARNER.

Witnesses:

HOWARD EGAN,
M. C. EGAN.
